UNITED STATES PATENT OFFICE

2,038,497

RECTIFIER ANODE

Othmar K. Marti, Wauwatosa, Wis., assignor to
Allis-Chalmers Manufacturing Company, Milwaukee, Wis., a corporation of Delaware

Application January 25, 1934, Serial No. 708,208

5 Claims. (Cl. 250—27.5)

This invention relates to improvements in the electrodes of electron discharge devices and more particularly to means for controlling the attachment of the electron discharge to the discharge receiving electrode of such device.

In an electron discharge device, the path between the electron emitting electrode and the electron receiving electrode does not include the entire area of the electrodes available for either emitting or receiving electrons. The flow of the electron discharge causes a large amount of heat to be produced at the contact points between the discharge and the electrodes, thus tending to cause deterioration of the electrodes or to produce excessive amounts of metallic vapor and also cause release of the gases or vapors occluded in the electrodes, thus increasing the vapor pressure within the device which tends to impair the operation of such device. The particular areas to which the discharge will attach on the electrode is determined by the relative position of the electrodes, by the unobstructed space available for the arc discharge and by the absence or presence of magnetic materials in or adjacent to the discharge path. If the discharge is forced to travel at a high velocity in the space adjacent the electrodes, the point of attachment of the discharge will likewise travel over the entire available electrode surface thereby insuring even distribution of the heat generated by such attachment throughout the entire electrode.

It is accordingly an object of the present invention to provide an electron discharge device electrode in which the point of attachment of the discharge to the electrode is forced to move over the surface area of such electrode during the period of such attachment.

Another object of the present invention is to provide an electrode for electron discharge devices of the vapor arcing type in which the point of attachment of the arc to the electrode is continuously moved over the surface of the electrode in a circular path due to the action of magnetic means associated with the electrode.

Another object of the invention is to provide an electrode for electron discharge devices with internal magnetic means operable in response to the flow of current through such electrode to cause movement of the point of attachment of the discharge over the entire surface area of the electrode.

Objects and advantages other than those above described will be apparent from the following description when read in connection with the accompanying drawings, in which

Fig. 1 is a vertical cross-sectional view of an electrode construction for use in an electron discharge device of the vapor arcing type and which embodies the present invention;

Fig. 2 is a partial vertical cross-sectional view 5 of a modified embodiment of an electrode head construction differing only in its structural details from the embodiment illustrated in Fig. 1;

Fig. 3 is a horizontal cross-sectional view, taken on the plane II—II of the embodiment illustrated 10 in Fig. 2;

Fig. 4 is a partial vertical cross-sectional view 15 of a modified embodiment of an electron receiving electrode construction in which a modified construction of magnetic means for causing movement of the point of attachment of the electron discharge is illustrated; and

Figs. 5, 6 and 7 are embodiments similar to the embodiment illustrated in Fig. 4, but differing 20 in the arrangement and construction of the magnetic means for causing movement of the discharge over the surface of the electrode

Referring more particularly to the drawings by characters of reference, the reference numeral 11 designates a portion of a casing for an electron 25 discharge device of the vapor arcing type such as are well known in the art and therefore do not require detailed showing in their entirety. A hollow skirted insulator 12 extends through an aperture in the casing 11 and is supported thereon 30 by a piece 13 secured to such casing or by other suitable means. The insulator is sealed into the aperture in casing 11 by means of a gasket 14 or by other suitable means well known to the art. The stem 16 of an electrode extends through insulator 12 in spaced relation therewith and the head, to be specifically described hereinafter, of the electrode abuts against one end of the insulator. The electrode head is held between the one end of the insulator 12 and an insulation 35 washer 17, resting on a flange 18, by compression of a spring 21 between the other end of the insulator and a nut 22 threaded on the stem 16. The spring compensates for the difference between coefficients of expansion of the several materials employed in the electrode construction and maintains mechanical contact and sealing engagement of the electrode head with the insulator. An arc guide or sleeve 23 is supported from a skirt of the insulator 12 50 and depends therefrom about the lower end of the insulator and the electrode head.

The electrode head is preferably formed in two portions 26 and 27, with the side wall portion 26 clamped between the end of the insulator 12 and 55

the flange 18 of the electrode stem 16 and the end or face portion 27 of the electrode head is screw threaded or otherwise attached to the portion 26 as will be described hereinafter. The two portions of the head may be made of any suitable conductive but preferably non-magnetic material and enclose a space within which is arranged a coil 28 of edge wound highly conductive magnetic material. The several turns of the coil 10 are insulated from each other by insulation 29 arranged and retained between such turns. The inlet or stem end of the coil is secured to the flange 18 by means of studs 32 and 33 and the outlet or head end 34 of the coil is secured to the electrode head. Current flowing through the stem 16 must therefore flow through the coil 28 to reach the head 26, 27. Such current creates a radial magnetic field about the coil and the head which causes an arc attaching to the head 15 to move in a circular path over the surface thereof. Due to the present construction, a sufficient number of turns of the coil 28 are present within the space enclosed by the head to insure movement of the point of attachment of the arc at 20 such speed as to revolve such point over the entire heat at least once during each one-third cycle of the alternating current supply voltage which is the working period of an electron receiving electrode when the discharge device is used 25 as a rectifier in the usual rectifying connections. The end portion 27 of the electrode head is preferably made concave to lengthen the path and thus to prevent attachment of the arc to the central portion thereof where the magnetic field would be relatively ineffective to cause rotation of such arc.

In the modification illustrated in Figs. 2 and 3, the inlet end 35 of the coil 28 is welded to a boss 36 extending from the flange 18 of the electrode stem 16. The outlet end of the coil is divided into a plurality of ears or lugs 37 bent over the electrode stem flange 18 and insulated from the flange by gaskets 38 and 39. The ears 37 are preferably formed only over the half of 40 the periphery of the electrode head farthest from the electron emitting electrode of the device and are in contact with such one-half portion of the head portion 26. Current can therefore flow only from the stem 12 through the boss 36, the coil 28, the ears 37 and the electrode head portion 26 to the head portion 27. Any tendency for the arc to attach only on the side of the electrode nearest the electron emitting electrode is thus counteracted by the resistance in the head material 45 from the point of contact of the ears 37 through the head portions 26 and 27 to the nearer side of such head. The arc is, of course, caused in addition to revolve over the head portion 27 by the rotating of field produced by the coil 28 as is described above.

The embodiment illustrated in Fig. 4 differs from the previously illustrated and described embodiments in a number of structural details. The head portion 27 in Fig. 4 is formed with a concavity of greater degree than was heretofore illustrated. The inlet end 35 of coil 28 extends adjacent the concavity of the head and is secured to the electrode stem 16 by a stud 33 as in Fig. 1. The several turns of coil 28 are formed 50 of material substantially square in cross-section and are insulated from each other and spaced from the head portions 26 and 27. The coil is again provided with ears or lugs 37 arranged as and for the purpose set forth above relative to 55 the construction illustrated in Figs. 2 and 3.

In the modified embodiment of the invention illustrated in Figs. 5, 6 and 7, the coil 28 is wound flatwise, the inlet end 35 of the coil 28 being welded to a ring 41 secured to the stem 16 by a stud 33. The outlet end of the coil is formed as a screw threaded cylinder 42 which is of such length in Figure 5 as to form the only means by which the head portions 26 and 27 are connected. The head is held between the stem flange 18 and the end of the insulator 12 as illustrated in Fig. 1. The coil 28 in the three embodiments now under consideration rests on an insulating plate 43 arranged in the bottom of the space enclosed by the head. In Figs. 6 and 7 the entire electron receiving surface of the head is made as an integral member 44. The head 44 is screw threaded to the cylinder outer coil end 42. In Fig. 6 the outer coil end 42 is also internally screw threaded for attachment to a head portion 46 clamped between the stem flange 18 and the end of the insulator 12. In Fig. 7 the outer coil end 42 is welded or otherwise fixedly secured to a portion of a split ring 47 which, with the head portion 46, is clamped between the stem flange 18 and the end of the insulator 12 as previously described.

In operation, the discharge within the device is initiated and maintained by any means known in the art. Upon positive energization of the electrode illustrated, current will flow through the stem 16 through the coil 28 and through the head portion secured to the outer end of the coil. Such current will flow continuously into the space between the electron receiving and the electron emitting electrode (not shown) in the form of a discharge which concentrates on a portion of the edge of the head portion 27. The flow of current through the coil 28 produces a magnetic field in which the lines of course are substantially parallel within the anode head and are divergent at the bottom portion of such head to form a field having a radial component. The lines of force close themselves in the space about the anode head. The discharge intersects the lines of force and is therefore driven in a direction tangential to the surface of the lower portion of the anode. The discharge will therefore move in a circular path and the point of attachment of such discharge on the head of the electrode will move in a circular path over such surface for the entire period of time during which the discharge is taking place. The velocity of the movement of the point of attachment of the discharge on the electrode is determined by the current intensity and the intensity of the magnetic field produced about the coil 28. Instead of being concentrated on only a portion of the electrode head, the production of heat due to such attachment of the discharge is distributed substantially uniformly over the entire area of the electrode. Deterioration of the electrode head or impairment of the internal conditions of the discharge device by release of gases, both deterioration of the head and release of gases being due to concentration of the attachment of the discharge to a small portion of the area of the head, is therefore prevented.

Although but a few embodiments of the present invention have been illustrated and described, it will be apparent to those skilled in the art that various changes and modifications may be made therein without departure from the spirit of the invention or from the scope of the appended claims.

It is claimed and desired to secure by Letters Patent:

1. An electron receiving electrode for an electron discharge device comprising a hollow insulator, a metallic stem extending through said insulator and having an enlarged flange portion, an electron receiving shell clamped between said insulator and the flange portion of said stem and insulated therefrom, and a solenoid arranged wholly within said shell and connecting said stem with said shell to provide the only path for current flow therebetween.
2. An electron receiving electrode for an electron discharge device comprising a hollow insulator, a metallic stem extending through said insulator and having an enlarged flange portion, an electron receiving shell divided into a plurality of portions and clamped between said insulator and the flange portion of said stem, an insulating member arranged between the flange of said stem and said shell, and a solenoid arranged wholly within said shell and connecting said stem with said shell to provide the only path for current flow therebetween.
3. An electron receiving electrode for an electron discharge device comprising a hollow insulator, a metallic stem extending through said insulator and having an enlarged flange portion, an electron receiving shell clamped between said insulator and the flange portion of said stem, and

a solenoid formed from material of rectangular cross section and formed with the greater dimension arranged horizontally and connecting said stem with said shell to provide the only path for current flow therebetween.

4. An electron receiving electrode for an electron discharge device comprising a hollow insulator, a metallic stem extending through said insulator and having an enlarged flange portion, an electron receiving shell clamped between said insulator and the flange portion of said stem, and a solenoid formed from material of rectangular cross section and formed with the greater dimension arranged vertically and connecting said stem with said shell to provide the only path for current flow therebetween.

5. An electron receiving electrode for an electron discharge device comprising a hollow insulator, a metallic stem extending through said insulator and having an enlarged flange portion, an electron receiving shell, an insulating member arranged between the flange of said stem and said shell, resilient means cooperating with said insulator and said stem to clamp said shell between said insulator and said insulating member, and a solenoid arranged wholly within said shell and connecting said stem with said shell to provide the only path for current flow therebetween.
